GUN CARRIER

Ralph Winfrey, 7012 Lexington Ave.,
St. Louis, Mo. 63121

Filed Apr. 28, 1972, Ser. No. 248,781

Term of patent 14 years

Int. Cl. D22—99

U.S. Cl. D22—13

FIG. 1

FIG. 1 is a front elevational view of the gun carrier, showing my new design;

FIG. 2 is a side elevational view thereof, and

FIG. 3 is a rear elevational view thereof.

The human figure is shown in broken lines for illustrative purposes only.

I claim:

The ornamental design for a gun carrier, as shown and described.
